(57) **CLAIM**

We claim the ornamental design for a path light device, as shown and described.

DESCRIPTION

FIG. 1 is a front perspective view of the design.

FIG. 2 is a second perspective view of the design.

FIG. 3 is a right side view of the design. The left side view is a mirror image of the right side view.

FIG. 4 is a front view of the design.

FIG. 5 is a rear view of the design.

FIG. 6 is a top view of the design; and,

FIG. 7 is a bottom view of the design.

The broken lines shown in the drawings represent portions of the path light device that form no part of the claimed design.
